UNITED STATES PATENT OFFICE.

MICHAEL EGAN, OF OGDENSBURG, NEW YORK.

AUTOMATIC LUBRICATOR FOR RAILROAD-CAR AXLES.

Specification of Letters Patent No. 13,749, dated November 6, 1855.

To all whom it may concern:

Be it known that I, MICHAEL EGAN, of Ogdensburg, in the county of St. Lawrence and State of New York, have invented a new and useful Device for Supplying Oil to the Axles of Railroad-Cars and other Journals, which I have described in the following specification and accompanying drawings with sufficient clearness to enable others of competent skill to make and use my invention.

My invention consists in the combination of a pin set eccentrically in the end of the axle, an arm or slide, which is operated by said pin to dip in the grease in a chamber below the axle and raise the grease to the axle in the manner hereinafter set forth.

In the accompanying drawings Figure 1 is a perspective view. Fig. 2 is a transverse section. Fig. 3 is a longitudinal elevation showing the box or oil chamber in section. Fig. 3 is an elevation showing in detail the plate A, and the arm B, said view being transverse to the axle. Fig. 5 is a longitudinal detail elevation of the same parts and some others with which they are connected.

The axle may be constructed in the usual manner for outside bearings, and the oil box with square sides and bottom. A pin D is set eccentrically in the end of the axle, and a connecting rod C extends from this pin to the ring H which is attached to the arm B which being thus connected to the pin D is caused to have a reciprocating vertical

motion as the axle revolves, and the horizontal part of the arm B is alternately plunged in the oil or grease below the axle, and raised up near enough to the journal to bring some textile stuff with which this part of the arm should be covered, in contact with the journal. The arm B is bolted to the slide A by the bolt F, the slide A serving to guide the motion of the arm B by being itself guided between the sides of the oil box. This arrangement secures a periodical and certain supply of oil to the journal which is not done by the ordinary methods of construction.

In the summer lard may be used to advantage—in the winter oil.

I do not claim in general terms feeding oil to the axle by an intermittent motion of the feeder or feeders produced by the revolution of the axle, or otherwise; neither do I claim the employment of a feeder which by either a constant or intermittent motion receives oil from a reservoir below, and deposits it on the axle.

I claim—

The arm B placed under the bearing and made to descend into the grease and rise to the journal at each revolution of the axle by being connected to the eccentric D or its equivalent substantially as herein set forth.

MICHAEL EGAN.
